DESIGN FOR A FLUE CAP

Sidney J. Heiman, St. Louis, Mo.

Application November 23, 1942, Serial No. 198,853

Term of patent 14 years

To all whom it may concern:

Be it known that I, Sidney J. Heiman, a citizen of the United States of America, residing at St. Louis, Missouri, have invented a new and original Design for a Flue Cap, of which the following is a specification, reference being had to the accompanying drawing, forming a part thereof.

Fig. 1 is an elevational view of one side of a flue cap showing my new design;

Fig. 2 is an elevational view of the other side thereof; and

Fig. 3 is a bottom plan view thereof.

I claim:

The ornamental design for a flue cap, as shown.

SIDNEY J. HEIMAN.
